UNITED STATES PATENT OFFICE.

MARTIN EMMITT HARRISON, OF PARNASSUS, PENNSYLVANIA.

WROUGHT-METAL POLE-ARM.

No. 860,864.

Specification of Letters Patent.

Patented July 23, 1907.

Application filed January 28, 1907. Serial No. 354,453.

To all whom it may concern:

Be it known that I, MARTIN EMMITT HARRISON, a citizen of the United States, residing at Parnassus, in the county of Westmoreland and State of Pennsylvania, 5 have invented certain new and useful Improvements in Wrought-Metal Pole-Arms; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to a new article of manufacture, and it comprises the making from a sheet of wrought 15 metal, of a telegraph pole cross-arm, which will be strong, durable and of simple construction, adapted to take the place of the wooden arm now in general use, together with means for supporting or attaching the insulator pins in position thereon, a means for securing 20 said arm to the pole, also the peculiar form of construction to give the arm the greatest lateral and direct strength, the bending and shaping of the top to form a water-shed for the preservation of the arm, together with other of certain details of construction, as will be 25 fully described hereinafter.

In the accompanying drawings;—Figure 1 is a side elevation of my improved cross-arm for telegraph poles, a part of which is shown in section and one of the ends broken away. Fig. 2 is a plan view of the same, also 30 having a part in section. Fig. 3 is a sectional end elevation taken on the line $y-y$, of Fig. 2, said view being shown on a larger scale. Fig. 4 is an enlarged side sectional elevation of a portion of the arm, showing a means whereby the insulator pins may be attached thereto. 35 Fig. 5 is a side elevation of a modified form of the cross-arm, showing the construction used in connection with wooden insulator pins such as are now in common use. Fig. 6 is an inverted plan view of the same. Fig. 7 is a 40 plan view of a small portion of the arm, showing the flanged openings for the reception of the shank of the insulator pin. Fig. 8 is an enlarged end elevation of the cross-arm, showing an insulator pin in position.

To construct a telegraph pole cross-arm in accordance 45 with my invention, I provide a piece of sheet metal, such as steel, of the proper width and length, and by means of suitable dies and press, bend the said sheet to a form substantially "U" shaped in cross section, (see Figs. 1 2 3 and 4,) leaving an open bottom, the sides 1 being parallel with each other, and the top higher along 50 its central longitudinal line than at either side, to form a water-shed 2. This water-shed 2, may be in the form of a curve, as at Fig. 3, or with angular sides arranged to precipitate the water during rain storms. Formed through the top of the cross-arm and at regular intervals, are openings for the reception of the shanks of the insulator pins 5, which are now manufactured,

for the purpose of sustaining wires, in two forms, the one of metal and the other of wood, both of which are shown in the drawings. These metal pins 5 are formed with a flanged threaded shank, and are attached and 60 made rigid with the cross-arm by means of a nut, (not shown) or otherwise. These metal pins I prefer to attach to the arm by means of a small casting, which consists of a body-portion 10, arranged within the arm and extending from one side to the other, said casting having a central threaded orifice for the reception of the threaded shank of the insulator pin 5. With this above-described means of attaching the insulator pins 5, it will not be necessary to permanently fix the same to the arm by rivets or otherwise, as said pin when screwed 70 tightly in position and the casting 10 extending from one side wall to the other, the threaded shank and flange of the pins will bind the parts rigidly together. The advantage of this means of attaching the pins 5 in position on the arm, will be to stiffen and support the 75 side walls against lateral pressure, the casting 10 being made to conform with the inner contour of the arm in all respects and to fit neatly therein. Surrounding the openings 6 for these insulator pins is a slightly elevated boss 4, pressed outward from the metal to form a 80 flat surface at right-angles to the plane of the sides 1 of the arm, and serves as a bearing for the flange of the insulator pin.

The sides 1 of the arm are formed with inwardly pressed ribs 3, and extend from the ends of said arm 85 inwardly to points a short distance at either side of the longitudinal center of the same; the object being to stiffen the side walls (by thus bending the metal) against lateral strain. To attach the cross-arm to the telegraph or other pole, bolt openings are formed 90 through the sides 1, at the middle or center of its length, the one opening in direct horizontal line with the other and through which a bolt 7 is passed, the said bolt being fitted with a separating piece 9 and projected through said pole and secured by a washer 95 and nut, in a manner common in the art. This parting piece 9, I prefer to form from a piece of pipe or tube, and is adapted to fit snugly within said arm and held in position by the bolt 7 passing therethrough. This parting piece 9 will hold the sides in 100 line against the strain caused by the tightening of the bolt 7. To further support the cross-arm in position on the pole 8, diagonal arranged braces 11 are attached to one of the sides of the arm by rivets 12 and the free ends attached to the pole some distance below the level of said arm.

The above description relates exclusively to that form of a cross-arm wherein metal insulator pins 5 are used, and in order that wooden pins 5' may be attached and used with this class of cross-arm, it is necessary to modify the details of construction respecting the means for supporting said wooden pins thereon 110

This modified form I have shown at Figs. 5 6.7 and 8, of the drawings, in which the cross-arm is formed from a plate or sheet of metal bent substantially the same as that previously described, and having the 5 side walls 1' at a portion of the middle substantially "U" shaped in cross section, and a portion of each lower half of said sides bent inwardly, leaving a narrow space 14, which construction serves the double purpose of strengthening the arm against direct and 10 lateral strains, and affords a means for supporting the lower end or shank of the wooden insulator pins 5', the metal at which points being expanded to fit neatly about opposite sides of said pins, as will be best seen by reference to Figs. 5 6 and 8, of the drawings. The water-shed 2' and bosses 4' are the same as before described, and if it is desired, the metal about the perimeter of the openings 6 for the insulator pins, may be flanged downward, (see Figs. 7 and 8) and made to present a broad surface for the support of 15 the upper part of the shank of said pin. The braces 11 may be attached to one of the side walls by rivets 12, or said rivets passed through both walls, as shown at Figs. 5 and 6. The means employed for attaching this form of cross-arm to the pole 8, is identical with 20 that of the other form shown and described.

These arms are made in various lengths and strength of material, galvanized or otherwise coated for protection against the weather, and have many advantages over the ordinary wooden cross-arm now in general use, the metal arm being lighter and of greater 25 strength and can be produced at about or somewhat less cost than said wooden arm, which latter is of carefully selected wood, free from knots and flaws, as of necessity, they must not only support the weight of 30 the wires, but at times, one or more "linemen", whose life, probably, depend upon the strength of said arm.

Another and important advantage in this wrought metal arm covered with a weather-proof material is, that it is practically indestructible, and has several times the life of the wooden arm.

40 This above-described pole arm is made from sheet metal, cut in blank form, and by several processes of bending, flanging, ribbing, &c., either cold or hot, bent by dies and presses into the proper form, and should not be classed with arms for the same purpose, 45 made from rolled shapes, such as—"I" beams, "channel" bars, "angle" bar, &c., which latter shapes are made under an altogether different process and are produced at several times the cost.

It is obvious that this sheet metal cross-arm may be 50 formed in a variety of different shapes best suited to the circumstances under which it is used. Therefore I do not wish to confine myself to the exact details of construction, but wish to claim all such modified forms as would come properly within the general 55 scope of the invention.

Having thus described my invention, what I claim, and desire to secure by Letters Patent, is:—

1. As a new article of manufacture, a pole arm of 60 pressed sheet steel.
2. As a new article of manufacture, a pole arm constructed from a single piece of sheet steel pressed into form.
3. As a new article of manufacture, a pole arm of sheet steel pressed into form and folded longitudinally to form 65 spaced sides and connecting web.

In testimony whereof, I affix my signature, in presence of two witnesses.

MARTIN EMMITT HARRISON.
